UNITED STATES PATENT OFFICE.

HERRMAN UNGER, OF NEW YORK, N. Y.

ORNAMENTED CLOTH.

SPECIFICATION forming part of Letters Patent No. 426,152, dated April 22, 1890.

Application filed April 11, 1889. Serial No. 306,805. (Specimens.)

To all whom it may concern:

Be it known that I, HERRMAN UNGER, of the city of New York, in the county and State of New York, have invented an Improved 5 Ornamented Cloth, of which the following is a specification, reference being had to the accompanying drawings, forming part hereof, in which—

Figure 1 represents a face view of the ornamented cloth made according to my invention. Fig. 2 is a section on the line *c c*, Fig. 1.

This invention relates to ornamented cloth of the class having a design of one character of surface finish upon a ground-work of another character of surface finish; and it consists in a cloth having a curled nap arranged in relief above a ground of straightened nap or fibers.

In the drawings, Fig. 1 represents at *a* the design in curled nap. Between this design at *b* lies the ground in straight fibers or nap. The curled nap is of the character of nap known in such fabrics as "Ratine," "Ondule," "Frise," "Elysian," "Whitneys," and the like. This 25 fabric may be produced by many different methods; but one method which I find very advantageous is to take a fabric having its en-

tire surface covered with curled nap—such as Ratine or Elysian—to cover some of this fabric, according to the design intended to be produced, with a pattern of stiff paper, sheet metal, or the like, and to brush the fabric which is exposed through the openings of such pattern, so as to lay the fibers that previously were curled into flat or straight form. Nothing 30 afterward—no handling, wetting, or other treatment of the fabric—will restore the flattened-out or straightened fibers into their previous curled condition, and I therefore have the advantage of producing a patterned 35 design which will retain throughout the pattern imparted to it, while heretofore the patterned designs that were known to me were liable, by wear, moisture, or the like, to become effaced.

What I claim is—

A fabric having a part *a* of its surface covered with curled nap and adjoining part *b* of its surface covered with straightened fibers, substantially as herein shown and described. 40 45 HERRMAN UNGER.
